UNITED STATES PATENT OFFICE.

FREDERICK HACHMANN, OF ST. LOUIS, MISSOURI, ASSIGNEE TO WILLIAM H. GREGG,
OF ST. LOUIS, MISSOURI.

BOOK COVER.

Application filed March 18, 1921. Serial No. 453,252.

To all whom it may concern:

Be it known that I, FREDERICK HACHMANN, a citizen of the United States, and resident of the city of St. Louis and State 5 of Missouri, have invented certain new and useful Improvements in Book Covers, of which the following is a specification containing a full, clear, and exact description, reference being had to the accompanying drawings, forming a part hereof.

My invention relates to improvements in book covers, and has for its object a book cover for sales purposes which is constructed entirely of metal and in which only one 15 hinge pin is made use of.

A further object is the construction of a model book cover having a single hinge pin, to which hinge pin are secured the cover, a pocket, and the clamp for holding the sales 20 tickets.

In the drawings:

Fig. 1 is a side elevation of my device;
Fig. 2 is a top plan view;

Fig. 3 is a top plan view showing the 25 front cover, thrown back, with portions thereof broken away;

Fig. 4 is a longitudinal sectional view of the front cover;

Fig. 5 is a plan view of the front cover 30 as blanked out and before being bent;

Fig. 6 is a similar view of the other cover;
Fig. 7 is a similar view of the pocket;

Fig. 8 is a similar view of the sales slip 35 clamp;

Fig. 9 is a perspective view of the clamp when being formed; and

Fig. 10 is a perspective view of the hinge pin.

In the construction of my device, I employ the covers 11 and 12, the cover 12 having the back 13 formed integral therewith.

Each of the covers are provided with the embossed ribs 14, which are for the purpose of strengthening the cover and also to prevent its scratching the furniture.

The cover 11 is provided along its one edge with a flange 15, which is adapted to be folded over, forming the receptacle 16, which is to receive one edge of a total sales ticket. The opposite edge of the cover is provided with a flange 17, which flange is adapted to be folded over the end of a strip 18, which forms the receptacle 19 for receiving the opposite edge of the sales ticket.

55 The cover 11 is also provided on its re-

maining edges with the flanges 20. These flanges are adapted to be folded over the flange 15 and the strip 18 and close the sides of the receptacles 16 and 19.

Adjacent the flange 17 are tabs or projections 21, which are adapted to be bent into eyelets for receiving the hinge pin. The rear or back cover is provided with flanges 22 and 23. These flanges are adapted to be beaded over, so as to form a 60 strengthening edge, as well as to eliminate sharp edges.

Formed in the back 12 are cut-away portions having one edge thereof serrated, leaving the teeth 24. These teeth are bent upwardly at right angles to the portion 12 and are adapted to engage with one side of the sales ticket block or book 25.

The portion 13 of the book cover 12 is provided with projections 26 and 27, the 75 projections 26 being bent into eyelets to receive the hinge pin, the portion 27 being bent around the strip 28, which connects the portions 29 formed on the edge of the clamping member 30. This clamping member is provided with projections 31, which are bent into eyelets and which pass around the hinge pin. The front edge of the clamp 30 is provided with serrations or teeth 32, which are bent downward at right angles 80 and engage the top surface of the sales ticket book 25. The clamp is held in engagement with the sales ticket book 25 by means of coil springs 33, one end of which bears against the clamp 30, and the other 90 end against the back 13.

Passing through the eyelets formed by the projections 21, 26 and 31 is a hinge pin 34, which has a central offset portion 35. Into this offset portion is secured the pocket 36. 95 This pocket is formed of a single sheet of metal and is provided for a portion of its one edge with a flange 37 and directly opposite the flange 37 with the flanges 38 and 39, the flange 39 being formed into an ear 100 which is secured to the offset portion 35 of the hinge pin 34.

The portion 40 of the pocket 36 is provided with a cut away portion 41, which is for the purpose of facilitating the removal of papers and memoranda placed in the pocket. The portion 40 is folded over the portion 36 and spaced apart therefrom, but has its edges 42 pressed closely to the portion 36, and the flanges 37 and 38 are bent 110

over these edges 42, thus closing the pocket along both sides. If desired, I may remove the pocket 36 from the cover without departing from the spirit or construction of my device.

Having fully described my invention, what I claim is:

1. A book cover, comprising a top cover, a bottom cover, a back integrally formed 10 with the bottom cover, eyelets formed on

the back and on the top cover, a hinge pin having an offset secured in said eyelets, a clamp secured to said hinge pin, and a pocket secured to the offset portion of the 15 hinge pin.

2. A book cover, comprising a top cover, a bottom cover, a back integrally formed with the bottom cover, eyelets formed on the back and on the top cover, a hinge pin having an offset secured in said eyelets, and a 20 spring actuated clamp secured to said hinge pin.

3. A book cover, comprising a top cover and a bottom cover, a back integrally

formed with the bottom cover, upwardly extending projections formed integral with the bottom cover adjacent the back, eyelets formed in the top cover and the back, a hinge pin extending through said eyelets, a spring-actuated clamp secured to said hinge pin and to the back, receptacles formed along the two edges of the top cover, and a pocket hingedly secured to the hinge pin.

4. A book cover, comprising a top cover, 35 and a bottom cover, a back integrally formed with the bottom cover, upwardly extending projections formed integral with the bottom cover adjacent the back, eyelets formed in the top cover and the back, a hinge pin 40 extending through said eyelets, a spring-actuated clamp secured to said hinge pin and to the back, and receptacles formed along the two edges of the top cover.

In testimony whereof, I have signed my 45 name to this specification.

FREDERICK HACHMANN.
